ABSTRACT OF THE DISCLOSURE

An X-ray apparatus includes means which automatically maintains to a predetermined level the brightness of an image appearing on the image intensifier. The brilliance of the image appearing on the image intensifier is monitored by a suitable photoelectric device, and the representations therefrom are applied to the winding of a balanced meter relay via the output of a form of balanced amplifier, the latter of which provides an output current which direction of current flow depends upon whether the output of the photoelectric monitoring device is above or below a predetermined level. An output of the meter relay is obtained from either one of two output terminals: If the meter pointer is substantially deflected from the reference center position in one direction, an output is produced at one terminal, and if the meter pointer is substantially deflected from the reference center position in the opposite direction, an output is provided at the second terminal. Each of the outputs is connected to suitable switching circuits which control the raising or lowering of the voltage of an adjustable power supply which supplies power to the X-ray tube. Suitable inhibit circuitry is provided so that should the switching circuits associated with one of the outputs of the meter relay be energized, the other switching circuit associated with the other meter relay output terminal is prevented from operating until the first switching circuit has been completely deenergized. The adjustable power supply includes a reversible A.C. motor containing two windings and a shaft suitably mechanically linked to a movable output tap on an autotransformer. The energization of one of the motor windings effects the rotation of the motor shaft, and hence, the movable tap, in a first direction; whereas the energization of the other winding results in the movement of the motor shaft, and, hence, the movable tap in an opposed direction. Suitably, each motor winding is connected in a respective one of two electrical circuits with the output of a respective one of the switching circuits associated with the meter relay output, and the power supply output voltage is adjusted, automatically, to raise or lower the voltages applied between the anode and cathode of the X-ray tube which provides a corresponding adjustment of the intensity of X-radiation emanating therefrom, and a corresponding change in the brilliance of the image appearing on the image intensifier tube.

This invention relates to an X-ray apparatus, and more particularly, to an X-ray apparatus in which the brightness of the fluoroscopic image is automatically regulated.

X-ray apparatus, by definition, includes a source of X-rays for directing X-rays through a patient. And, inasmuch as the patient is inhomogeneous in its density, the more dense portions of that body absorb a greater amount of the incident X-radiation than other less dense portions thereof. Accordingly, as the generated X-rays are applied over a certain area on one side of the patient, the X-radiation which penetrates through that area forms

2

an image or field of high and low intensities of X-radiation. Conventionally, this image is received by an image convertor located in the apparatus on the other side of the patient which converts this X-ray image into a visual image. Conventionally, this conversion is accomplished with either a screen of X-ray sensitive phosphorescent material commonly termed "a fluoroscopic screen" or an image intensifier.

In the more sophisticated modern equipment, the image on the fluoroscopic screen or image intensifier is monitored by a television camera, such as a vidicon or orthicon which then transfers the visual image to a television receiver located at a remote position where a visual image may be monitored and observed without exposing the radiologist to stray X-radiation.

In the very best apparatus, the image intensifier is used in place of the fluoroscopic screen. Basically, such a device contains an X-ray sensitive faceplate which converts an incident X-ray image into a visual image and then electronically amplifies the visual image, presenting an intensified visible image on a second smaller sized faceplate. Conventional image intensifiers amplify the level of the received image by a factor of about 3000. The output of the image intensifier is then available at the second faceplate to permit observation of the enhanced visible image. Alternatively, the image intensifier is also used in conjunction with a television pickup system so that the image may be observed on a remotely located television set.

In giving an X-ray examination there is quite often a need for the radiologist to adjust the intensity of X-radiation generated in order to increase the brilliance of the visual image to a level which he finds desirable. Likewise, in many instances the radiologist must reduce the level of X-radiation generated to reduce the brilliance of the image either because the image is too bright or because it subjects the patient to a higher level of radiation than is necessary under the circumstances. However, with most presently available apparatus this adjustment must be performed manually. And, in order to effect such a manual adjustment, the radiologist must subject the patient to needless exposure while he is making the adjustment and determining whether the observed visual image is suitable: This procedure is obviously undesirable.

In the more sophisticated commercially available systems having television pickup cameras, such as the vidicon or orthicon, automatic controls are provided to which the manual adjustment of source intensity is an adjunct. As is well known, the output of the television camera and likewise the television receiver can be both manually and automatically adjusted to increase or decrease the brilliance of the visual image without changing the intensity of the X-ray source. Assuming that the image received by the vidicon camera is within a suitable range of brilliance, the vidicon can be adjusted to produce higher or lower brilliance images at the output of the television receiver. Conventionally, such television pickups contain automatic gain control circuits which, electronically, automatically maintains the output of the vidicon tube to a predetermined level within a small range of values, and thus provides for an image of constant brilliance. There are instances, however, where the intensity of the X-ray source should be increased so that the output of the image intensifier is within a range of brilliance within the threshold level of the vidicon tube. While the vidicon system has proved satisfactory, it and the gain control circuitry associated therewith are relatively very expensive. For example, a recently developed television pickup tube called the "Plumecon" performs the same essential functions as the vidicon tube, but is only

one-tenth as expensive. Unfortunately, however, there appears to be no available inexpensive control circuits for use with the Plumecon that can hold the output signals therefrom to a present level. Accordingly, while a pickup tube of the Plumecon type serves to reduce the cost of remote image displays for X-ray apparatus, without an inexpensive intensity control circuit the quality or control of the available image with such tube type is reduced.

Therefore, it is an object of the invention to automatically regulate the intensity of fluoroscopic image in an X-ray apparatus without requiring the intervention of the operator;

It is a further object of the invention to provide an X-ray apparatus in which the brightness of the visual image is automatically maintained at the preset level;

And, it is a still further object of the invention to provide an automatic brilliance control suitable for use in an X-ray apparatus having remote displays.

Briefly stated, the invention includes a photosensitive pickup for monitoring the level of illumination from the visual image appearing on a fluoroscopic screen or other image converter. The output of this monitoring pickup is also monitored by electrical circuitry which signals a departure of the pickup output above or below a predetermined level. A source of X-rays which generates X-rays proportional in intensity with the voltages applied from an adjustable power supply is provided. A voltage control means is provided which is responsive to the signals generated by the monitoring means and causes the power supply voltage to increase or decrease in response to the output of the monitoring means, signaling the departure of said pickup signal above or below predetermined levels, respectively.

Further in accordance with the invention, the monitoring means comprises a meter relay and includes relay means responsively connected to first and second output terminals of the meter relay.

Moreover, the voltage control means, in accordance with another aspect of the invention, comprises a motor driven autotransformer in which the motor is reversible and suitable connections are made between the relay and the motor control windings to cause the motor to be properly driven in either the forward or reverse direction.

The foregoing and other advantages and features which are believed to be characteristic of the invention, both as to its organization and method of operation, together with further objects and advantages thereof is better understood from the following description considered in connection with the figure of the accompanying drawing which illustrates one embodiment of the invention by way of example.

The figure of the drawings shows a conventional source of X-rays, tube 1, having an anode 2, and a heater or filament winding 3 which also functions as the electron emitting cathode. An adjustable power supply for the X-ray tube includes two portions. One portion is the high voltage and rectifying section 4. The second portion is a low voltage control section 6.

The low voltage control section 6 contains an autotransformer 8 having a winding 10 which is connected to a source of A.C. currents suitably the 115 A.C. voltage. A slideable electrical contact or tap 12 is positionable along the turns of winding 10 to provide selections of a desired output voltage. As is conventional, the autotransformer steps down the line voltage in proportion to the position of the slideable tap 12 to the shaft of a reversible A.C. motor 16 which permits the conversion of the motor shaft rotation to the linear up and down movement of slideable contact 12.

Reversible motor 16 is conventional and contains two stator windings 18 and 20, schematically indicated in the figure, for controlling the direction of rotation of the motor shaft. One side of each winding is connected to ground potential. The other end of winding 18 is connected to a source of current, suitably 115 volt A.C. line

voltage, in series with normally open relay contacts CR1. The remaining end of the other winding 20 is likewise connected to the same source of current in series with normally open relay contacts CR2. The output from the low voltage control section 4 is taken from autotransformer 10 and is connected to the input of high voltage power section 4, by a connection to primary winding 22 of a high voltage transformer 23. Transformer 23 includes a high voltage secondary or output winding 24 and a low voltage or filament winding 26. The output of high voltage winding 24 is connected across one diagonal of a conventional bridge rectifier 28. The other or output diagonal of bridge rectifier 28 is connected between the anode 2 and filament 3 of X-ray tube 1. As is conventional, a filter capacitor 29 is connected across the output diagonal of the bridge rectifier. The filament winding 26 is connected across the filament terminals of filament 3.

The "fluoroscopic" or receiving apparatus in the X-ray equipment is located on the side of a patient 30 opposite source 1 and is schematically indicated by the dashed lines 32. This includes image converting apparatus 34, such as a fluoroscopic screen or other conventional apparatus, which converts a received X-ray image into a visual image. Phosphorescent screens or X-ray image intensifier tubes are ordinary examples of such converters.

A photosensitive pickup, a photoresistor 36, is located in housing 32 adjacent the fluoroscopic screen so as to receive the light from any visual image appearing on the screen. Photoresistor 36 is connected in an electrical circuit between a source of voltage (—) and the input 38 of a balanced amplifier schematically represented by dashed lines 40. Balanced amplifier 40 includes a first PNP transistor 42 in a dual output amplifier circuit. Transistor 42 has an emitter 44, a collector 46, and a base 48. A source of bias voltage is represented by E. One output terminal provides a positive eight volts relative to ground potential while the other terminal provides a negative eight volts relative to ground potential, although the total voltage between the terminals is 16 volts.

Resistors 50 and 52 are connected in series across source E and the juncture of the series connection is connected to input 38 and one end of a base resistor 54. Resistor 54 is connected at its other end to the base 48, transistor 42. A first load resistor 56 is connected between the positive bias voltage and emitter 44. A second load resistor 58 is connected between the collector 46 and the negative bias voltage from source E. A second PNP transistor 60 is provided. Transistor 60 contains an emitter 62, collector 64, and base 66. A connection is provided from the emitter 44 of transistor 42 to base 66 of transistor 60 in series with a base resistor 68; and a base bias resistor 70 is connected between the positive source and base 66. Emitter 62 is connected to the positive source in series with a resistor 72. Collector 64 is connected to output terminal 39 in series with a load resistor 74.

A third transistor 76 contains an emitter 78, collector 80, and a base 82. Base 82 is connected to the collector 46 of transistor 42 in series with a base resistor 84. A base bias resistor 86 is connected between base 82 and the negative source terminal. A resistor 88 is connected between the positive source terminal and emitter 80. A load resistor 90 is connected between collector 78 and output terminal 39.

Meter relay 92 is a conventional current measuring and switch device which includes a winding 93 and a pointer 94 positionable along a calibrated scale. Normally pointer 94 rests at the center of the meter scale. However, current flow in one direction through 93 effects movement of the pointer to the right and current flow through winding 93 in the opposite direction causes a current proportional pointer movement to the left.

One end of winding 93 is connected to output terminal 95 which in turn is connected to ground potential in series with a current limiting resistor 96. The other end of

winding 93 is connected to input terminal 97 which in turn is connected to output terminal 39 of the balanced amplifier in series with normally open relay contacts CR56. Input 97 is additionally connected to a series circuit of a normally closed relay contact CR56B, and a capacitor C to the negative terminal of the voltage source.

The juncture of the series connection between contacts 56B and capacitor C is connected to the positive terminal of the source in series with normally open relay contact CR56C and resistor 98.

Meter relay 92 conventionally includes a pair of photoresistors 100 and 101 and a light source 102 that normally illuminates the photoresistors and which is energized by any suitable source, such as battery V. Pointer 94 includes a shutter portion 103. Photoresistor 100 is connected between ground potential and a first output terminal 104, and photoresistor 101 is connected between a second output terminal 106 and ground potential.

The meter relay output terminals are connected to the inputs of electrical switching circuits. The first switching circuit includes an amplifier 108, an electronic switch 110, a relay driver circuit 112, and a relay CR1. A second electrical switching circuit includes an amplifier 114, an electronic switch 116, a relay driver circuit 118, and a relay CR2. In substance, both switching circuits are of identical construction and include substantially identical and conventional elements and connections. Therefore, in the interest of brevity, only the first switching circuit is discussed in any great detail. However, it is understood that such conventional details apply equally to the second switching circuit.

Amplifier 108 includes a conventional NPN transistor 120 having a base 121, emitter 122, and collector 123. A base input resistor 124 is connected between an input 125 and base 121. A biasing resistor 126 is connected between the positive bias source and input 125. A second bias resistor 127 is connected between base 121 and ground. A load resistor 128 is connected between the positive bias source and collector 123, and emitter 122 is connected through a resistor 129 to ground.

Electronic switch 110 includes a PNP transistor 130 having its base 131 connected through a base bias resistor 132 to the positive bias source. Additionally, the base 131 is connected to the output of transistor 120 in series with resistor 133. Transistor 130 has its emitter 134 connected through diode 135 to the positive source. The collector 136 is connected through a load resistor 137 to ground potential.

An NPN transistor 138 in relay driver circuit 112 includes a base 139, emitter 140, and collector 141. A forward poled diode 142 in series with a resistor 143 is connected between collector 136 of transistor 130 and base 139. A base bias resistor 144 is connected between base 139 and ground. A capacitor 145 is connected between the output of diode 142 and ground. Capacitor 145 and resistors 143 and 144 form an RC time delay circuit. Emitter 140 is connected in series with a forward poled diode 146 to ground potential. Another forward poled diode 147 is connected between collector 141 and the winding of relay CR1, which in turn is connected to the positive voltage source. A diode 148 is connected across relay winding CR1 for conventional surge protection.

A clamp circuit 150 is connected to the output of the relay driver circuit. A PNP transistor 151 therein has its base 152 connected to the output of the relay driver circuit in series with a resistor 153 and diode 154. Its collector 155 is connected directly to ground potential. A bias resistor 156 is connected between base 152 and emitter 157. The output of clamp circuit 150 is taken by a connection from the emitter 157 and applied to input 113 of amplifier 114 in the second switching circuit.

In like manner, the output of amplifier 114 is connected to the input of electronic switch 116, which in turn has its output connected to the input of relay driver 118 in the second switching circuit. The output of relay driver 118

is connected to relay winding CR2 and to the input of a clamp circuit 160. The details of clamp circuit 160 are substantially identical with that of clamp circuit 150. The output of clamp circuit 160 is connected to the input 125 of amplifier 108 in the first switching circuit. Inasmuch as amplifier 114, switch 116, relay driver 118, and clamp circuit 160 are of a construction identical in detail with that heretofore described for the corresponding elements in the first switching circuit they are schematically represented only by dashed lines.

A relay CR56 is connected in series with foot switch 162 to a source of electrical potential. In the idle condition, relay contacts CR56, CR56A, and CR56C are open and relay contact CR56B is normally closed. Thus, winding 93 of meter relay 92 is disconnected from the output of balanced amplifier 40. Instead, winding 93 is connected through break contacts CR56B to a capacitor C which absorbs any transient voltages, avoiding any spurious deflection of meter pointer 94 from the center position of the scale.

The radiologist operates foot switch 162 to energize relay winding CR56. Relay CR56 closes contacts CR56D which connects the power supply of the source, CR56A which connects the output of balanced amplifier 40 to input winding 93 in meter relay 92, and opens contacts CR56B which disconnects capacitor C from winding 93. Any charge accumulation on capacitor C is discharged through resistor 98 to the positive source upon closure of relay contacts CR56B.

Relay CR56 includes the previously discussed contacts CR56, CR56B, and CR56C. In operation the 115 A.C. volt source is applied to winding 10 of autotransformer 8 in power supply section 6. Autotransformer 8 steps down the line voltage to a level proportional to the position of movable tap 12. The output voltage appearing at contact 12 is applied to primary winding 22 of transformer 23 in the high voltage section 4. The voltages applied across primary winding 22 are stepped up through transformer action to a high voltage which appears across secondary winding 24. The high voltage is applied across one diagonal of a conventional bridge rectifier circuit 28 for rectification.

Bridge rectifier 28 converts the A.C. voltage into a D.C. voltage across the other diagonal. This D.C. voltage in turn is filtered by smoothing capacitor 30 and applied between anode 2 and filament 3 of the X-ray tube. A portion of the electrical energy supplied to primary winding 22 is stepped down by transformer action to a low filament voltage appearing across secondary or filament winding 26. The heater voltage is applied across the terminals of heater 3 which causes thermal emission within X-ray tube 1.

X-ray tube 1 generates X-rays which are directed through a patient, indicated by dashed lines 30, and emanate out of the patient to form an X-ray image upon screen 34 in receiving apparatus 32. This image is converted into a visual image by the fluorescent screen. The light emanating from the visual image illuminates adjustable photoresistance 36. Since the resistance of photoresistor 36 is an inverse proportional function of the light level, a value of resistance is established which is related to the level of illumination incident thereon. Current flowing through photoresistor 36 establishes a signal or voltage at input 38 of balanced amplifier 40 which biases base 48 of transistor 42 to a predetermined value. Transistor 42 normally conducts current which flows from the positive source through load resistor 56, emitter 44, collector 46, and through load resistor 58 to the negative source.

The output voltage across each of load resistors 56 and 58 is coupled to the base of transistors 60 and 76, respectively. At a predetermined level of output voltages from transistor 42, each of transistors 60 and 76 conducts substantially the same amount of current, and hence, offer the same overall resistance considered as a voltage

divided network. This current may be considered to flow from the positive source through resistor 72, emitter 62, out collector 64 through resistors 74 and 90, emitter 78, out collector 80 through resistor 88 to the negative voltage source. Because both transistors offer the same resistance to current between the positive and negative bias source, the voltage under at the output of balanced amplifier 40 and the juncture of resistors 74 and 90 is normally zero or ground potential. Since ground potential is applied both to inputs of meter winding 93, the meter pointer remains at its center position.

If the light level from on screen 34 is lower than a predetermined level, photoresistor 36 assumes a larger value of resistance. This causes the potential at base 48 to become more positive which in turn causes an increase in the current between the emitter and collector of PNP transistor 42, which is reflected in a lower voltage at collector 44 and at the base 66 of transistor 60 and a higher voltage at emitter 46 and at the base 82 of transistor 76.

Accordingly, transistor 76 conducts current more heavily while transistor 60 reduces its conduction. Accordingly, the juncture of resistors 74 and 90 is placed at a more negative potential which results in current flowing from ground potential through resistor 96, meter winding 93, to the output 39 of balanced amplifier 40 and causes the deflection of meter pointer 94 to the right.

A predetermined deflection of meter pointer 94 results in the shutter portion 103 thereof moving to a position shielding photoresistor 100 from the source of light 102. Accordingly, the level or resistance of photoresistor 100 is increased, and accordingly, there is a reduction in current between resistor 126 in amplifier 108 and photoresistor 100 to ground potential. This results in a more positive voltage at input 125 and base 121 of NPN transistor 120.

Transistor 120 decreases conduction and provides a higher output voltage from collector 128 through resistor 133 to the base 131 of transistor 130. Transistor 130 senses the higher level of voltage and fully conducts current from the positive source, diode 135, emitter, collector, and resistor 137 to ground. This provides a positive output across resistor 137. This output voltage is applied to base 139 of NPN transistor 139 through diode 142 and resistor 133. Additionally, capacitor 145 is charged. Transistor 138 conducts fully causing current to flow from the positive source through relay winding CR1, diode 147, between collector and emitter 141 and 139, diode 146 to ground potential and lowers the voltage at the output juncture of diode 147 and relay winding CR1.

Relay winding CR1 closes its normally open contacts CR1 connected in series with winding 20 of reversible motor 16 in power supply control section 6. Current flows through the winding and causes motor 16 to revolve its shaft in the clockwise direction. By means of linkage 14, slidable contact 12 is raised up the turns of the autotransformer winding 10. Accordingly, the voltage, V, applied to primary winding 22 of transformer 23 is increased, resulting in a larger voltage across secondary winding 24 and, hence, across the anode 2 and filament 3 of tube 1.

Since the radiation produced by X-ray tube 1 is proportional to the voltage applied between its anode and cathode, the increase in that voltage increases the intensity of the generated radiation. Since the intensity of the radiation is greater, the intensity of the visual image that appears on screen 34 is likewise more brilliant.

Photoresistor 36 monitors the increase in illumination and, accordingly, decreases in resistance in proportion to the increase in the level of illumination. Since balanced amplifier 40 is preadjusted to provide a zero or ground potential at its output upon photoresistor 36 presenting a predetermined level of resistance at input 38, when the level of illumination on screen 34 is raised to the

predetermined level, current through winding 93 ceases and meter pointer 94 is rebalanced in its center position. Accordingly, the shutter portion 103 of meter pointer 94 uncovers photoresistor 100, which again permits light source 102 to illuminate photoresistor 100. Accordingly, photoresistor 100 is lowered to a substantially lower normal level of resistance, which in turn is presented to input 125 of amplifier 108 via the first output terminal 104 of meter relay 92. Electronic switch, transistor 130 ceases conduction and removes the voltage input to relay driver circuit 112.

Although the output of electronic switch 110 is no longer presented at the input of relay driver circuit 112, transistor 138 continues to conduct until capacitor 145 discharges through resistors 143 and 144 over a predetermined period of time. Subsequently, transistor 138 ceases conduction, deenergizing the winding of relay CR1. After the release time of the relay, relay contacts CR1 are restored to their normally open position, which in turn 20 interrupts current through reversible motor winding 20. Motor 16 stops and accordingly leaves slidable contact 12 of autotransformer 8 at its last position.

During the period in which transistor 138 of relay driver circuit 112 conducts, the voltage appearing at the input 25 of clamp circuit 150 is reduced from the normal value. Accordingly, current flows through resistor 156, resistor 153, and diode 154 making base 152 slightly more negative in polarity relative to emitter 157. Accordingly, transistor 152 conducts current from emitter 157 through collector 155 to ground potential.

Since the voltage drop between the emitter and collector is slight, the output of clamp circuit 150 is effectively reduced to a zero or ground potential. Accordingly, the input 113 of amplifier 114 in the second switching circuit 35 is grounded. This prevents any input signal from the second output terminal 106 of meter relay 92 from energizing the second switching circuit while relay CR1 in the first switching circuit is operated. This is necessary to prevent both relays CR1 and CR2 from being operated 40 at the same time, and hence, to preclude energizing both windings of motor 16 simultaneously. This can occur if there is a rapid swing of the meter pointer from the right over to the left. Obviously if both windings of motor 16 are simultaneously energized, the motor would burn out.

Where overillumination occurs, the resistance of photoresistor 36 is reduced from the preset level and the output 45 of the balanced amplifier 40 becomes more positive relative to ground potential, because transistor 62, therein, conducts more fully than transistor 76. Accordingly, current flows in a direction from the output terminal 39 through meter winding 93, resistor 96, to ground potential. This current in the meter winding causes the meter pointer 94 to swing to the left. In the instance of sufficient deflection, the pointer shutter portion 103 covers photoresistor 50 101 connected between the second output terminal 106 of the meter relay and ground. The level of resistance of photoresistor 101 is raised which accordingly places input 113 of amplifier 114 in the second switching circuit at a higher potential. This increase in level of input voltage is amplified by amplifier 114 and applied to electronic switch 116. Electronic switch 116 changes its state from a nonconducting to a conducting condition providing an output voltage in the same manner as described for switch 110. Relay driver circuit 118 detects the output 55 and operates in the same manner as relay driver 112, previously described, the winding of relay CR2 and the output voltage supplied to the input of clamp circuit 160 from the illustrated side of winding CR1 is lowered, clamp circuit 160 is thus operated and reduces the potential at the input 125 of amplifier 108 in the first switching circuit to prevent inadvertent operation of the first switching circuit, while the second switching circuit operates. Relay CR2 closes its normally open contacts CR2,

70 which in turn completes a current path between a

source of power and the second winding 18 in reversible motor 16. In this instance, motor 16 rotates its shaft counterclockwise. Through conventional mechanical linkages 14, motor 16 shaft lowers slidable tap 12 to reduce the voltage V applied across primary winding 22 of transformer 23. Since the output of the high voltage section is proportional to the level of voltage applied to primary winding 22, the high voltage applied between anode 2 and cathode 3 of X-ray tube 1 is reduced as the position of tap 12 is lowered.

Accordingly, the intensity of radiation emitted from X-ray tube 1 is lowered and the level of illumination of the visual image appearing on screen 34 is reduced. This change is monitored by photoresistor 36 which accordingly increases in resistance as the level of incident light decreases.

Upon the attainment of a predetermined lower level of illumination and larger level of resistance of photoresistor 36, the output voltage of balanced amplifier 40 is again reduced sufficiently near zero volts and accordingly the meter relay pointer is again rebalanced at or near its center position. Accordingly, the shutter portion 103 of meter pointer 94 again uncovers photoresistor 101 and the second output terminal 106 of meter relay 92 appears again as a high resistance. Electronic switch 116 restores to its nonconducting state and removes the input to relay driver circuit 118. At the completion of a predetermined period of time, relay driver circuit 118 deenergizes relay winding CR2 and removes the input signal from input of clamp circuit 160. Clamp circuit 160 removes the inhibiting or ground potential from input 125 of amplifier 108 in the first switching circuit. At the completion of a relay release interval, relay CR2 restores and opens its normally open contacts CR2. This interrupts the flow of current into the winding 18 of motor 16. Accordingly, motor 16 halts, leaving the slidable contact 12 at its last position.

It is apparent that in this manner the level of illumination appearing on screen 34 is maintained automatically at a predetermined level while the radiologist conducts a fluoroscopic examination of his patient. This is accomplished automatically without the intervention of the radiologist, and thus, frees the radiologist for his examination and precludes any unnecessary exposure of the patient inherent in those prior art circuits which permit the patient to be exposed while the radiologist manually adjusts the radiation intensity to a desired level. Additionally, the invention permits the use of a relatively inexpensive television pickup camera, such as the Plumecon, without the expensive and complicated brightness control circuits formerly used in the orthicon or vidicon systems.

It is further noted that in addition to control of the power supply voltage, indirectly, by photodetector 36, the voltage control circuits can, instead, be placed under the control of other (not illustrated) ancillary equipment. Thus, for example, assuming foot switch 162 is not operating, and hence, contact CR56A, which connects amplifier 40 to winding 93 of meter relay 92, remains open, and that the ancillary apparatus, symbolically illustrated as Q, is connected to terminal 97 and includes sources of positive and negative voltages that may be selectively applied to terminal 97. Thus, a current of the selected polarity may flow between ground, resistor 96, coil 93, and the source in Q. The meter relay will then be actuated in the same manner as previously discussed for photoelectric control.

Thus, if a source of positive voltage in Q is selected and is applied to terminal 97, the meter pointer 94 swings in one direction and exposes one of the photocells in the meter relay to meter light 102, causing the associated switching circuit to actuate reversible motor 16 which in turn commences movement of movable tap 12 in the corresponding direction. Likewise, by selectively connecting the negative voltage source included within such ancillary equipment to terminal 97, current flows to meter

winding 93 in the direction opposite to that in the preceding case. Accordingly, the other photoelectric cell in meter relay 92 is exposed to the source 102 causing operation of the associated switching circuit and energization of the other winding of reversible motor 16, which in turn drives movable tap 12 in the opposite direction; hence, changing the voltage applied between the anode and cathode of X-ray tube 1.

While the illustrated embodiment shows certain specific amplifier switches, transistors, and relays, and uses a meter relay in order to enable visual indication of the departure from normal or any visual image, it is apparent that other equivalent circuits exist which accomplish the same function without a meter relay and with details different than those used to illustrate the invention.

Thus, while these specific details have been used to illustrate the invention, it is not the intention to limit the invention to those details.

I claim:

1. An X-ray apparatus comprising: a controllable intensity source of X-rays; converter means for converting an X-ray image into a visible image to permit observation thereof; light monitoring means for sensing the light level of said visible image on said converter means and producing an output representative thereof; and control means responsive to the change in output of said light monitoring means above or below a predetermined output level for lowering or raising, respectively, the intensity of said source of X-rays; said control means comprising: means for amplifying the output of said light monitoring means; control signal means connected to the output of said amplifier for producing a first control signal in response to a decrease in the output level of said amplifier below a predetermined level and for producing a second control signal in response to an increase in the output level of said amplifier above a predetermined level; said control signal means including a meter relay having a meter pointer normally at a reference position for producing a first output at a first terminal in response to the deflection of said meter pointer to a first predetermined position in one direction from said reference position and for producing a second output signal at a second terminal in response to the deflection of said meter pointer to a second predetermined position in an opposed direction from said reference position, said meter relay having a current carrying meter coil for positioning said meter pointer; first switch means responsive to an output from said first meter relay output for closing a first electrical circuit to provide said first control signal; second switch means responsive to said second meter relay output for closing a second electrical circuit to provide said second control signal; first inhibit means for inhibiting operation of said second switch means during operation of said first switch means; and second inhibit means for inhibiting operation of said first switch means during operation of said second switch means.

2. The invention as defined in claim 1 wherein said controllable intensity source comprises: an X-ray tube having an anode and cathode; and wherein said control means further comprises adjustable power supply means for applying an output voltage between said anode and cathode; and means responsive to operation of said first switch means for increasing the output voltage of said power supply and responsive to operation of said second switch means for decreasing the output voltage of said power supply.

3. The invention as defined in claim 2 wherein said adjustable power supply means includes: a motor having a shaft; an autotransformer having a movable output tap; linkage means coupling motion of said shaft to said movable output tap; said motor including a first winding responsive to current flow therethrough for effecting rotation of said shaft in a first direction and a second winding responsive to current flow therethrough for effecting rotation of said shaft in a second direction.

ing said first winding in circuit with said first electrical circuit and means connecting said second winding in circuit with said second electrical circuit.

4. The invention as defined in claim 2 wherein, said control signal means further includes: a balanced amplifier means connected to said amplifier means for producing an output voltage of one polarity in response to an output from said light monitoring means being above a first predetermined level and for producing an output of opposite polarity in response to an output from said light monitoring means being a predetermined amount below said level.

5. An X-ray apparatus comprising: a controllable intensity source of X-rays; converter means for converting an X-ray image into a visual image to permit observation thereof; control means for changing the intensity of said source of X-rays; said control means including: first means for producing a voltage of one polarity in response to a first selection to increase the intensity of said X-ray source and for producing a voltage of opposite polarity voltage in response to a second selection to decrease the intensity of said X-ray source; a meter relay having a meter pointer normally at a reference position for producing an output at a first terminal in response to the deflection of said meter pointer to a first predetermined position in one direction from said reference position and for producing a second output signal in response to said meter pointer attaining a second predetermined position from said reference position in an opposed direction; said meter relay having a current carrying meter coil for positioning said meter pointer; means connecting said first means in circuit with said meter coil; first switching means connected to said first terminal and responsive to a first meter relay output for closing a first electrical circuit; second switching means responsive to said second meter relay output

for closing a second electrical circuit; first inhibit means for inhibiting operation of said second switching means in response to operation of said first switching means; second inhibit means for inhibiting operation of said first switching means in response to operation of said second switching means; and wherein, said controllable intensity source includes an X-ray tube having an anode and cathode; adjustable power supply means for supplying an output voltage between said anode and cathode; and means responsive to operation of said first switching means for increasing the output voltage of said power supply, and responsive to operation of said second switching means for decreasing the output voltage of said power supply; said adjustable power supply means including a motor having a shaft; an autotransformer having a movable output tap; linkage means coupling motion of said shaft to said movable output tap; said motor including a first winding responsive to current flow therethrough for effecting rotation of said shaft in a first direction; and a second winding responsive to current flow therethrough for effecting rotation of said shaft in an opposed direction; means connecting said winding in circuit with said first electrical circuit; and means connecting said second winding in circuit with said second electrical circuit.

UNITED STATES PATENT OFFICE
CERTIFICATE OF CORRECTION

Patent No. 3,548,208

Dated December 15, 1970

Inventor(s) Joseph Battista

It is certified that error appears in the above-identified patent and that said Letters Patent are hereby corrected as shown below:

Col. 7, line 1, "diveder" should be --divider--

CLAIM 3, Col. 10, line 75 through Col. 11, line 3 should read as follows:

of said shaft in an opposed direction; and means connecting said first winding in circuit with said first electrical circuit and means connecting said second winding in circuit with said second electrical circuit.

Signed and sealed this 31st day of August 1971.
